UNITED STATES PATENT OFFICE.

CHARLES E. GOULD, OF FREMONT, MICHIGAN, ASSIGNOR OF ONE-HALF TO
GEORGE TATE, OF SAME PLACE.

BOB-SLEIGH.

SPECIFICATION forming part of Letters Patent No. 544,221, dated August 6, 1895.

Application filed April 4, 1895. Serial No. 544,473. (No model.)

To all whom it may concern:

Be it known that I, CHARLES E. GOULD, a citizen of the United States of America, residing at Fremont, in the county of Newaygo and State of Michigan, have invented certain new and useful Improvements in a Self-Supporting Knuckle to be Used in the Construction of Bob-Sleighs; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of my invention is to provide an efficient coupling between the runner and cross-bar of the sled, by means of which the runner will be permitted to have a rocking movement so as to adjust itself to the inequalities of the road; and the invention consists in providing the cross-bar of a bob-sled on its upper side with a casting having a convex upper surface with which a bar attached to the runner engages, the underside of the cross-bar having attached thereto a casting provided with depending bearing-surfaces and a central recess which engage a casting shaped to receive the same, the latter casting being secured to the upper edge of the runner, the parts being held in place by a bar or "rave," which is bolted at its ends to the runner, all as will be hereinafter fully set forth and particularly pointed out in the claim.

In the accompanying drawings, forming part of this specification, Figure 1 is a perspective view showing the parts in position for use. Fig. 2 is a perspective view showing the parts separated, and Fig. 3 is a sectional view.

A designates the bolster, which is connected to the cross-bar B in the usual manner—that is to say, by means of a king-bolt—bearing-plates being interposed between the bolster and cross-bar. To the upper side of the cross-bar, and near the ends thereof, are secured castings B', said castings having a convex bearing surface b, upwardly-projecting side flanges b', and beyond the flanges projections which are apertured for the passage of the connecting-bolts. To the under side of the cross-

bar and on a line below the castings B' are attached castings C having side projections, with apertures which register with the apertures in the castings above, the apertures being connected by apertures through the cross-bar so that both castings are secured to the cross-bar by the same bolts. The castings C are provided with a depending bearing-surface having a central concave recess c forming semicircular bearing-surfaces c', which are rounded as shown, the sides tapering off to the projecting sides hereinbefore referred to.

D designates a casting which is secured to the upper edge of the runner and is provided with a semicircular recess or bearing-surface to correspond with the bearing-surface of the casting C, the casting D having a central web or projection d, from which the bearing-surface rounds off as shown, so that when the parts C and D are placed in engagement with each other lateral movement will be prevented.

E designates what I term the "rave," which consists of a bar bent to present inclined members connected by a horizontal portion, as shown. The ends of this bar or rave are rigidly bolted to the runner, and when the parts of the knuckle-joint are placed in position the horizontal portion of the bar or rave bears upon the casting B', thus holding the parts C and D securely in position by frictional contact. When the parts are thus connected the complementary bearing-surfaces of the parts C and D are in engagement with each other, so that they can rock in the direction of the runner and the bar or rave E will prevent displacement.

By the construction hereinbefore described the center of the rocking movement is at a point adjacent to the under side of the cross-bar, thus positioning the center of movement very high up, so that in practice there will be a comparatively small range of movement between the cross-bar and upper part of the bar or rave E.

I am aware that prior to my invention it has been proposed to connect the runners of a bob-sled to the cross-bar by means of suitable fixtures to allow a rocking movement of the runners with respect to the cross-bar, and I do not therefore claim such invention broadly;

but as far as I am aware the castings or fixtures heretofore used have been connected by bolts which pass through slots or elongated openings.

5 I am also aware that runners have been connected to the cross-bar so as to have a sliding movement thereon, the parts being held together and against vertical displacement by means of long bolts placed at the front and 10 rear of the knee and connected to a bar which extends over the cross-bar and is attached to the runner.

I am also aware that it has been proposed to connect the runners and cross-bar by a joint 15 which is coupled by means of a transverse bolt.

What I claim as new, and desire to secure by Letters Patent, is—

20 A knuckle-joint for sled knees consisting of castings B' and C having convex recesses to provide bearing surfaces having side walls

and projections with apertures which register with each other so that both castings are secured to the cross-bar by the same bolts, a casting D having side bearing surfaces and a 25 central web d which are complementary to the bearing surfaces and recesses of the casting C attached to the under side of the cross-bar, and a bar or rave E having a horizontal portion which engages with the convex bearing 30 surface of the casting B' secured to the upper side of the cross-bar, the ends of the bar or rave being attached to the runner, substantially as shown, whereby the bar or rave holds the parts in engagement with each other, for 35 the purpose set forth.

In testimony whereof I affix my signature in presence of two witnesses.

CHARLES E. GOULD.
